LIGHTING TOWER

Jackson A. Partlow, Rock Hill, S.C., assignor to Zip-Up
Lighting Tower Company, Inc., Rock Hill, S.C., a cor-
poration of South Carolina

Filed June 27, 1966, Ser. No. 2,821

Term of patent 14 years

(Cl. D54—1)

FIGURE 1 is a perspective view of the lighting tower looking up from the bottom thereof and showing my new design;

FIGURE 2 is an enlarged fragmentary perspective view of the upper portion looking down upon the top thereof and with the upper dotted line portions removed and the lower portion of the tower broken away for convenience of illustration;

FIGURE 3 is a view similar to FIGURE 1 of another embodiment of the lighting tower;

FIGURE 4 is a view similar to FIGURE 2 of an upper portion of the lighting tower shown in FIGURE 3 looking down upon the top thereof and with the upper dotted line portions removed and the lower portion of the tower broken away for convenience of illustration;

The dominant feature of the full line portions resides in these portions shown in full lines. The characteristic feature of my design resides in the upper portion of the

lighting tower and more specifically in the depending surrounding relationship of the cage portion to the upper portion of the supporting mast. Also, the other sides of the lighting tower are substantially identical to those shown in the drawings.

I claim:

The ornamental design for a lighting tower, substantially as shown and described.
